UNITED STATES PATENT OFFICE.

WALTER S. ANDERSON, OF DETROIT, MICHIGAN, ASSIGNOR TO EARL HOLLEY, OF DETROIT, MICHIGAN.

VENT PLUG FOR PERMANENT MOLDS.

Application filed March 9, 1925. Serial No. 13,994.

The object of this invention is to provide improved venting means for metal molds. One of the most serious difficulties experienced when casting iron in metal molds is that air is trapped, causing imperfections in the castings. If holes are drilled sufficiently large not to clog with dirt and dust, iron flows in and seals them.

Figure 1 shows a mold in elevation.

10 Figure 2 shows a cross sectional elevation on the plane 2—2 of a pair of molds.

Figure 3 shows a cross sectional elevation on the plane 3—3 of Figure 2.

In the figures, A is the sprue. B is the 15 gate leading to the mold C. D is a plug. E is a boss provided for said plug. The plug D is provided with three flats F F F. These flats are arranged to provide gaps preferably .008" to .010" in width (not over .015"). G 20 and H are the mold castings themselves, in which the mold cavities C C are provided. The sprue A, gate B, and mold cavity C are surrounded by a bead J which provides the matching surface between the two halves G 25 H of the mold, as shown in the Phillips Patent #1099997.

Operation.—The two halves G H of the mold, having been brought together so that the matching surface J J are in contact with each other, the iron is poured in through the sprue holes A, gate B, into the mold cavity C. As the mold cavity C fills up with molten metal the displaced air rises and escapes through the three flats F F F arranged on the circumference of the plug D. By this means a good sound casting is produced free from surface and other imperfections due to trapped air. The vents F F F are of such a size that the iron cannot follow the air through it. If holes having the same dimen-

sions as the flats F F F are drilled into the casting they easily clog up with dirt and dust, and moreover holes as small as this are expensive to drill because of the tool breakage.

45 These molds are intended to be coated with a thin refractory coating and a superimposed coating of lampblack, as set forth in the Meloche Patents #1453593 and #1492694. Iron is poured in the mold when the mold 50 is at a relatively high temperature, above 600° F.

55 For the sake of clearness the ejection devices used in conjunction with these molds have been omitted.

What I claim is:—

1. In a metal mold having a cavity therein, a vent plug adapted to close said cavity and provided with a flat surface, an air passage between the wall of said cavity and said 60 plug opposite said flat surface not over .015".

2. In a metal mold, a vent plug provided with a depression on the surface of the plug through which air may escape but iron cannot flow.

3. In a metal mold having a cavity therein, a cylindrical plug adapted to close said cavity, a relatively wide gap between the plug and the wall of said cavity of such a width that molten metal cannot flow therethrough but through which air can escape.

4. In a metal mold having a cavity therein, a vent plug adapted to close said cavity, an opening between said plug and said cavity having a maximum opening of .015" in 75 width, said opening being located in that portion of the mold in which air would otherwise collect.

In testimony whereof I affix my signature.
WALTER S. ANDERSON.
